Primary Examiner — Karen S Acker(74) *Attorney, Agent, or Firm* — Cook Alex Ltd.; R. Blake Johnston(57) **CLAIM**

The ornamental design for a chair, as shown and described.

DESCRIPTION

FIG. 1 is a perspective view of the chair;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The features drawn in broken line in FIG. 2 depict portions of the chair that form no part of the claimed design.

1 Claim, 4 Drawing Sheets(56)
